UNITED STATES PATENT OFFICE.

JULES CARPENTIER, OF PARIS, FRANCE.

MAGAZINE-BOX FOR PHOTOGRAPHIC FILMS.

No. 832,237.

Specification of Letters Patent.

Patented Oct. 2, 1906.

Application filed July 8, 1905. Serial No. 268,893.

To all whom it may concern:

Be it known that I, JULES CARPENTIER, a citizen of the Republic of France, residing in Paris, France, have invented certain new and useful Improvements in Magazine-Boxes for Photographic Films, of which the following is a specification.

This invention has for its object a magazine-box containing sensitized films used in 10 photography, which box is placed immediately at the back of a camera like a magazine and permits of changing the films, together with another similar box or receiver arranged back to back with the magazine-box and 15 which takes the exposed films as they are used.

The accompanying drawings show by way of example this magazine-box, the characteristics of which will be fully explained in the 20 following specification.

Figures 1 and 2 are respectively a longitudinal section and a sectional plan view of a receiver-box. Fig. 3 is a section thereof on line A B of Fig. 1. Fig. 4 is a section on line 25 C D. Fig. 5 is a plan of a portion of the paper band supporting the film. Fig. 6 shows two superposed magazines placed in the sheath of the photographic apparatus, the lower box serving as a receiver for the exposed 30 films.

The changing-box A, inside which are placed two magazine-boxes, one being full and the other empty, is open at one end and closed at the other by a suitable movable 35 door a. It is provided at its upper part with an opening through which the film is exposed and with two cross-bars b b, against which the magazine containing the films abuts. The sides of the box have stops c c 40 near the door a, which serve to keep the film-boxes inside the sheath.

The magazine used consists of a card-box B, having in its top an opening d, corresponding with the surface to be exposed. On the 45 bottom of the box B are fixed one or more springs e for pushing the plate f, whereon is the pile of films D, toward the open top, each film being supported by a paper band r. The magazine-box, which when empty may 50 be used as a receiver for the exposed films, has an opening or slot y made in the wall opposite the opening x only sufficiently wide to permit the passage of the extended narrow portion of the band or bands of paper r, to 55 which the films are attached. This opening

y may be made light-tight by a band y', of velvet; but this is not essential.

The ends of the films may be gummed together, so as to ease their introduction into the box. They may also be fastened together by a metallic clamp in case gum is not desirable.

The two small sides of the magazine-box are formed at one end by a little piece of wood j and at the other end by the piece of 60 wood z, having the groove or opening y. This box is provided near the piece j with two screw heads or projections w, which engage the stops c, and so limit the movement of the magazines inside the sheath of the photographic apparatus.

In order to use an empty magazine as a receiver for the films as they are exposed, the operator proceeds as follows: A magazine-box full of films, together with an empty 75 magazine, are placed back to back, and the protruding ends of the paper bands r, supporting the films, are passed into the empty magazine through the opening x. It is necessary to press back the false bottom f, 80 which urges forward the films when the magazine is full, or else the ends of the bands r would encounter the said bottom and be prevented from advancing. The paper bands r are then pulled and passed through the 85 opening y, and the ends that are fastened together may now be cut by scissors or other convenient means to free them from each other, so that each band r can be pulled separately. The full and empty magazines are 90 now placed together in the frame or sheath or change-box A of the camera, the former being placed face to the lens. The door a of the sheath is then shut, and the apparatus is ready for use. The box shown is for taking 95 stereoscopic views and has therefore a pair of separated openings in its face, as is indicated in Fig. 6. When it is desired to expose the first film, the said film must be uncovered, as it is protected by a loose sheet of black paper 100 r' of the same shape as the band or strip r. (Shown in Fig. 5.) To this end the operator pulls the end of the first paper which protrudes through the opening y of the lower box until the larger part abuts against the 105 sides of the piece z, which limits the width of the opening y. In consequence the band of the black paper which covered the non-exposed film enters the empty box and closes the opening d in said box. When the first 110

film has been exposed and it is desired to change it, the said film is drawn by its paper band *r* and places itself in the empty magazine behind the black paper band, and it is only necessary to tear the paper *r*, protruding outside the apparatus, and so on for all films contained in the magazine-box. This device makes it very easy to take the exposed films for development without disturbing the non-exposed films. To this end it suffices to separate the boxes from each other, and after having taken out the exposed films the magazine-boxes are replaced, as aforesaid.

15 The films may be attached to the wide ends of the paper bands *r* by means of gummed wafers, as indicated in Fig. 5, or by any other suitable means.

Having now particularly described and ascertained my invention and in what manner it is to be performed, I declare that what I claim is—

1. The combination with a combined band and film having a stop at one end of the film, 25 of a box having an open face for exposing said film and having at one end a slot through which the full length of said combined band and film may pass, and at the other end a slot through which said stop and 30 consequently the film cannot pass.

2. The combination with a combined band and film having a shoulder at one end of the film, of a box having an open face for exposing said film and having at one end a slot 35 large enough to pass the wider portion of said combined band and film, and at the other end a shorter slot passing only the narrower portion of said combined band and film, whereby said narrower portion may be 40 used to draw the film through the larger slot of a similar storage-box but not through such storage-box.

3. The combination with a series of shou- 45 dered bands carrying films, of a storage-box, and a similar exposing-box in which said films are carried, having an open face for exposing said films and having at one end a slot large enough to pass the wider portions of said bands, and at the other end a shorter 50 slot passing only the narrower portions of said bands, said narrower portions projecting out of the larger slot of said box, whereby they may be used to draw the films through

the larger slot of the storage-box but not through such storage-box. 55

4. The combination of a frame, and two separate boxes, one an exposing-box having an open face for exposing films therein, and the other a storage-box, said boxes having passages in their ends and adapted to be carried in said frame with said passages close together, so that the films after exposure in one box may be transferred to the other box. 60

5. The combination of a frame, and two separate boxes, one an exposing-box having 65 an open face for exposing films therein, and the other a storage-box, said boxes having passages in their ends and adapted to be carried in said frame with said passages close together, so that the films after exposure in 70 one box may be transferred to the other box, and stops in said frame for determining the positions of said boxes therein.

6. The combination of a frame, and two identical separate boxes having open faces 75 for exposing films therein and having passages in their ends and adapted to be carried back to back in said frame with said passages close together so that the films after exposure in one box may be transferred to the other box. 80

7. The combination of a frame, and two separate boxes, one an exposing-box having an open face for exposing films therein, and the other a storage-box, said boxes having 85 passages in their ends and adapted to be carried in said frame with said passages close together, so that the films after exposure in one box may be transferred to the other box, said frame being open at one end to provide 90 access for transferring said films, stops in said frame and on said boxes for determining the position of the boxes therein, and a door at the end of the frame for permitting inspection and access to the corresponding ends of 95 said boxes and for holding them in place with their stops engaging the stops of the frame.

In witness whereof I have hereunto signed my name in the presence of two subscribing 100 witnesses.

JULES CARPENTIER.
